(57) **CLAIM**

The ornamental design for an antler vehicle ornament set, as shown and described.

DESCRIPTION

FIG. 1 is a front elevational view of a first antler of an antler vehicle ornament set showing my new design;

FIG. 2 is a right side elevational view thereof;

FIG. 3 is a rear elevational view thereof;

FIG. 4 is a left side elevational view thereof;

FIG. 5 is a top plan view thereof; and,

FIG. 6 is a sectional view thereof taken along the line 6-6 of FIG. 1.

The bottom is plain and unornamented; the dashed lines form no part of the claimed design; the dash dot dash lines depict light emanating from LEDs and the second antler of the antler vehicle ornament set comprises a mirror image of each of the views showing the first antler.
